Primary Examiner — Jonathan J Han*Assistant Examiner* — Christen Pilar Brown(74) Attorney, Agent, or Firm — Banner & Witcoff, Ltd.CLAIM

The ornamental design for a shoe, as shown and described.

DESCRIPTION

FIG. 1 is a side view of a shoe showing my new design; FIG. 2 is a front perspective view thereof;

FIG. 3 is a front view thereof;

FIG. 4 is an opposite side front perspective view thereof; and,

FIG. 5 is an opposite side view thereof.

The broken line immediately adjacent to the shaded area defines the bound of the claimed design and forms no part thereof. The two broken lines within the shaded area in the toe region represent seams that form no part of the claimed design. The broken lines depicting the remainder of the shoe form no part of the claimed design.
